UNITED STATES PATENT OFFICE

EMIL SALOMON, OF TULSA, OKLAHOMA

DESIGN FOR A SALESMAN'S COMMERCIAL BUTTONHOLE EMBLEM

Application filed May 4, 1931. Serial No. 39,685. Term of patent 3½ years.

To all whom it may concern:

Be it known that I, EMIL SALOMON, a citizen of the United States, residing at Tulsa, in the county of Tulsa and State of Oklahoma, have invented a new, original, and ornamental Design for Salesman's Commercial Button-Hole Emblem, of which the following is a specification, reference being had to the accompanying drawings, forming a part thereof.

I claim:

The ornamental design for a salesman's commercial button-hole emblem, as shown.

EMIL SALOMON.
